(57) **CLAIM**

The ornamental design for a headlight for a vehicle as shown and described.

DESCRIPTION

This application contains subject matter related to the following co-pending U.S. design patent applications:
Application Ser. No. 29/813,885, filed Nov. 2, 2021 and entitled “Headlight for a Vehicle;” and
Application Ser. No. 29/826,883, filed herewith and entitled “Headlight for a Vehicle”.

FIG. 1 is a front view of a headlight for a vehicle according to the design;

FIG. 2 is a right, front perspective view thereof;

FIG. 3 is a left, bottom perspective view thereof;

FIG. 4 is a right side view thereof;

FIG. 5 is a left side view thereof;

FIG. 6 is a top view thereof;

FIG. 7 is a bottom view thereof; and,

FIG. 8 is a rear view thereof.

The broken lines in the drawings and the lightened areas within the broken lines illustrate portions of the headlight for a vehicle that form no part of the claimed design.

1 Claim, 8 Drawing Sheets
